HYDRAULICALLY ACTUATED CRIMPING TOOL

Howard R. Fischer and Marcel P. D'Haem, Utica, N.Y., assignors to Chicago Pneumatic Tool Company, New York, N.Y., a corporation of New Jersey

Application July 10, 1957, Serial No. 670,976

18 Claims. (Cl. 81—15)

This invention pertains to a pneumatically powered compressing tool that is compact in size and is adapted to be held in the palm of the hand when operated. The tool is particularly suited for use in wire terminal crimping operations, and the like.

A general object of the invention is to provide an improved and practical pneumatically operable compressing tool of small size that is held in the hand when operated.

A feature of the invention is a highly efficient mechanical movement of elements powered by a piston driven wedge, whereby a movable jaw is caused to be compressively closed upon a stationary jaw.

A further feature of the invention is a practical trigger controlled arrangement of valves for effecting pneumatically upon each actuation of the trigger a single reciprocating movement of the piston driven wedge.

Another feature of the invention is a manually operable push button control arrangement for opening by pneumatically powered means the jaws of the tool to enable insertion of work material between them.

Another feature of the invention is a manually operable latch for safely holding the jaws locked in open position after the push button has been released.

A still further feature of the invention is an interlock safety arrangement, whereby a compressive action of the tool cannot be effected while the jaws are held in open position.

Another object of the invention is to provide a practical hand tool wherein all of the foregoing features are embodied.

The invention further lies in the particular construction of its various parts, and also in their general arrangement and cooperative association with one another to effect the results intended herein.

The foregoing and other objects, features and advantages of the invention will appear more fully herein-after from a consideration of the detailed description which follows, taken together with the accompanying drawings wherein an embodiment of the invention is illustrated. It is to be expressly understood, however, that the drawings are for purposes of illustration and description, and they are not to be construed as defining the limits of the invention.

In the drawings:

Fig. 1 is a longitudinal section through the tool;

Fig. 2 is a plan section on the line 2—2 of Fig. 1;

Fig. 3 is a cross section on the line 3—3 of Fig. 2;

Fig. 4 is a cross section on the line 4—4 of Fig. 2;

Fig. 5 is an enlarged sectional view showing the latch block in a latched condition, holding the jaws of the tool in fully open position;

Fig. 6 is a cross section on the line 6—6 of Fig. 5;

Figs. 7 and 7a are enlarged sectional views which schematically show the condition of the tool preparatory to effecting operation of the tool and a consequent crimping action upon terminal wire elements received between the dies, Fig. 7a showing the valve system in normal position;

2

Figs. 8 and 8a are enlarged sectional views which schematically show the condition of the tool upon completion of the forward stroke of the tool in effecting a crimping action;

Fig. 9 is a sectional view which schematically shows the relation of the control and pop-off valves at the end of the return stroke of the wedge and while the trigger is still held depressed; and

Fig. 10 is an enlarged sectional view which shows the valve system immediately after the trigger has been actuated.

The tool illustrated in the accompanying drawings includes a housing 20 providing a drive or work piston chamber 21 which is closed at its rear by a valve block or head 22. The opposite end of the piston chamber opens through a reduced area 23 into a forward chamber 24. The latter opens out through the bottom and front end of the housing. Disposed within chamber 24 in parallel spaced relation to each other is a pair of side bearing plates 25, 25'. These plates, as appears in Figs. 2 and 3, project in part through the front end and through the bottom of the housing. An upstanding arm 26 of a yoke member 27 is rigidly retained between the forwardly projecting portions of the side plates by means of pins 28. The inner walls of the side plates serve as bearing faces for a tail end or block portion 29 of a ram 31. The latter has a reduced cylindrical shaft 32 which continues forwardly from the ram block 29 and slides through a complementary opening in the yoke arm 26. A ram jaw 33 has a tail piece 34 retained in an end bore of ram shaft 32 by a suitable pin. Jaw 33 represents the movable member of a pair of opposed jaws. The other jaw 35 is stationary, and is an integral part of the yoke member. Jaws 33 and 35 are adapted to accommodate separate halves of a pair of wire terminal crimping dies 36, 37 (Fig. 1). The particular dies shown are for purposes of illustration only. The dies serve, when closed under pressure, to effect a crimping action on wire terminal elements 38 disposed between them (Figs. 7 and 8).

The movable jaw 33 is normally held in its forward or closed position (Fig. 1) by a spring loaded holding piston 39. The latter is pneumatically operable to move against this spring load so as to draw the ram jaw to open position. This piston moves in a cylinder 41 formed by the housing in the upper area of chamber 24. An open rear end of this cylinder is closed over by a washer plate 42 which abuts against a suitable snap ring retained in an internal groove of the cylinder. The piston carries a rod 43 which is slidable through the washer plate into the upper rear area of chamber 24. The free end of an upstanding piece 44 of a draw bar 45 is retained at 46 upon an externally projecting end of the piston rod. The draw bar slides in a channel track 47 formed in the underside of the piston cylinder. Integral with the forward end of the draw bar is a fork having a pair of depending fingers 48. The latter depend freely into a pair of vertical slots 49 formed on opposed inner faces of the arms 51 of a bifurcation formed in the rear of the ram block 29. Coil spring means 52 disposed about the piston rod 43 and loaded between the piston and the washer plate constantly urges the piston to a normal forward position (Fig. 1), wherein the fingers 48 of the draw bar hold the movable jaw in its forward or closed position.

Pneumatic control means (Figs. 1, 2, 4, 5, 7, 7a) is provided to actuate the holding piston 39 to cause the movable jaw 33 to be drawn to its open position. To this end, the valve block 22 has a supply inlet 53 which is adapted for connection by a hose line, not shown, to a source of pressure air. A branch passage 54 from

this inlet leads through the valve block and housing to a chamber 55 of a check valve 56. The latter is continuously under the load of pressure air in passage 54, and normally seals chamber 55 off from a passage 57. The latter passage communicates by radial port 58 through the chamber 59 of an interlock slide member 61 with a further passage 62 leading to the chamber of cylinder 41 ahead of the holding piston. The check valve has a stem 63 which extends freely through passage 57 into an enlarged counterbore 64 that opens to the outside of the housing. Threaded on the end of this stem is a push button 65 that projects in part from the housing, and has a loose fit in counterbore 64. The check valve is unseated by manually depressing the push button. While the check valve is unseated, pressure air flows through the associated passages to the holding piston 39, after sliding the interlock valve 61 to the left against the load of a light spring 66, whereupon the holding piston is forced to the right against the load of its springs 52, and the draw bar 45 is caused to draw by means of its fingers 48 the movable jaw 33 to its fully open position, as appears in Fig. 5. While the push button is manually held depressed, an O-ring 67 on the inner end of the latter seats upon a shoulder 68 and prevents escape of pressure air around the outer diameter 25 of the push button.

After push button 65 is manually released and the check valve thus reseated, jaw 33 is returned to its normally closed position by the holding piston as the latter restores under the load of spring means 52. As piston 39 restores, air in the piston chamber ahead of the piston vents to atmosphere around the outer diameter of the push button.

The primary function of the pneumatically operable holding piston is to permit jaws 33 and 35 to be drawn apart so as to enable insertion of uncrimped wire terminal elements 38 between the dies 36, 37. After the latter action is effected and the push button is released, the holding piston under the load of its springs carries the die 36 of the movable jaw into abutment with the terminal wire elements 38 and thereby holds the latter in place (as in Fig. 7). Pneumatically powered means is provided to next pressurize the jaws and dies so as to effect a crimping action upon the wire terminal elements.

This pneumatically powered pressurizing means includes a lever bar 69 having a slightly rounded nose 71 at its forward end. This nose extends into the bifurcation formed in the rear of the ram block 29 and it abuts against the back wall 72 of the bifurcation. The nose end of the lever is loaded into abutment with wall 72 by a pair of coil springs 73 disposed along opposite sides of the lever. Projecting ends of a cross pin 74 at opposite sides of the lever serve as anchors for the springs at one end. Ears 75 at the rear of the bifurcated arms 50 of the ram block serve to anchor the springs at the opposite end. A cross shaft 76 projects through opposite sides of the rear portion of the lever. Each projecting end of this shaft is fitted with bearings carrying a roller 77. An eccentric cam face 78, forming the rear end of 55 the lever, is normally in close proximity to the peripheral surface of a large roller 79 which has a stationary position relative to the housing.

Roller 79 is carried by bearings fitted on a stationary cross shaft 81. The ends of this shaft are supported in complementary holes formed in opposed bossed portions 82 of the side plates 25, 25'. The side plates and cross shaft 81 are retained in the housing by headed bushings 83 fitted in opposite sides of the housing and by bolts 84 threaded through the bushings into opposite ends of the cross shaft.

When the movable jaw 33 is drawn to open position (Fig. 5) by the holding piston as previously described, the eccentric cam end 78 of the lever is caused to ride down over the large roller as the opposite nose end 71

of the lever pivots against the back wall 72 of the bifurcation of the ram block. The underside of the lever is limited in its downward movement by a stub roll pin 80 supported in the side plate 25. An underlip 85 formed at the forward end of the lever, and an upper lip extension 86 of a spring plate mounted on the latter, respectively extend under and over the ram block 29, whereby the lever is guided in a vertical plane during its pivoted movement.

If it is desired that jaws 33, 35 remain open for any length of time, locking means is provided to lock them in this open position, so as to avoid the necessity of continuously holding the push button 65 depressed. This locking means comprises (Figs. 1, 5, 6) a latch block 87 which is arranged below ram block 29. This latch block is vertically slideable between the side plates 25, 25'. It is guided in this sliding movement by the rear end wall 88 of the yoke arm 26 and by a pair of stub roll pins 89 carried by the side plate 25. When the ram member is drawn to its fully open position, the tail block 29 thereof is drawn clear of the latch block 87 and the cylindrical shaft 32 of the ram member is moved to a position above the latch block. A semi-circular trough 91 in the latter is adapted to engage about the ram shaft in front of a shoulder 92 of the ram block, when the latch block is moved upwards. Shoulder 92 abuts against the latch block in this moved position of the latter, whereby the ram member is held in its moved or fully open position.

A manually operated cam lever 93 is arranged to effect up or down movement of the latch block and consequent engagement or disengagement of the latter with the ram member. This lever is substantially triangular and is pivoted at its vertex on a cross pin 94 supported in the housing. A nosed corner of this lever extends into an under-bifurcation 95 of the latch block and is pivoted therein on a pin 96 supported by the arms of the bifurcation. A finger 97 projecting from the lever to the outside of the housing enables manipulation of the lever, whereby the latch block may be vertically raised or lowered relative to the ram shaft. The latch block retains its moved position by friction means provided by a pair of ball elements 98. These are spring loaded outwardly of the latch block so as to frictionally engage 45 opposed faces of the side plates 25, 25'.

After the latch block is disengaged from the ram shaft, the movable ram jaw 33 will be automatically returned by the spring loaded holding piston 39 to normal position. As the ram jaw restores, the lever bar 69 will be caused to pivot in a vertical plane to its normal horizontal position, as in Fig. 1, being aided in this respect by the side springs 73. In the event of an abnormal overrise of lever 69 above its horizontal position, the upper rear area thereof will strike the underside of the closely overhanging draw bar 45. In this action the spring lip 86 will be forced down upon the tail block and will yield slightly, whereby damage to the lever, that might otherwise occur if this upper lip were rigid, is avoided.

If wire terminal elements 38 have been previously disposed between the dies for a crimping action, the movable jaw 33 and lever 69 will restore under the action of the holding piston to the degree as limited by the thickness of the wire terminal elements, and the lever 69 will then depend angularly, as appears in Fig. 7. This lever is actuatable by a pneumatically driven wedge 99 so as to effect a compressive crimping action of the dies upon the wire terminals.

This wedge has a normal position, as in Fig. 1, between the piston chamber 21 and the forward chamber 24. An axially extending tail shank 101 of the wedge is retained by a suitable pin in a forked member 102. The forked member has an axial extension which is retained by a threaded portion and nut means 103 to a drive or work piston 104. The latter reciprocates in piston chamber 21. Lengthwise of the underside of the wedge is a chan-

nel track 105 in which is slidably received an upper portion of an elongated thick center rail 106 of a ladder roller cage 107. This center rail or bar carries transversely thereof a succession of pin type rollers 109 which, with the exception of at least the first one 108, are needle bearings. The ends of the several rollers project from opposite sides of the center bar about midway of the upper and lower surfaces of the latter, whereby an upper rail portion and a lower rail portion are provided (Figs. 3, 4). The lower portion is adapted to ride in an underchannel track 111 formed lengthwise of a flat surface of an upper portion of a trigger supporting piece 112 of the tool.

The latter piece or section is assembled between the lower portions of the side plates 25, 25'. To this end, the side plates provide a pair of opposed shoulders 113 (Figs. 3, 4) lengthwise of their inner faces. A narrow underportion 114 of section 112 depends between these shoulders and projects between the bottoms of plates 25, 25' to the outside of the housing. The upper portion of the trigger supporting section provides longitudinal shoulders 115 which overlie the shoulders 113 of the side plates. The projecting ends of the rollers of the roller cage are adapted to roll upon the shoulders 115 as the center rail 106 of the cage moves in the trackway 111. Depending legs 116 of the wedge freely straddle the center rail 106 and are adapted to ride over the rollers of the roller cage as the wedge moves.

As the wedge is driven forwardly by the work piston 104, it rapidly and smoothly rides over the needle bearings of the roller cage to engage and to pivot the ram lever 69 upward. In this movement of the wedge relative to lever 69, the side rollers 77, which hang in part below the under-edge of the lever are engaged by a cam varying upper surface 117 of the moving wedge. A slot 118 in the nose of the wedge is provided to avoid interference with a projecting lower corner 119 of the lever, so that the latter corner will not strike the wedge. As the rising cam surface of the rapidly moving wedge moves against and under the rollers 77, it pivots the ram lever 69 upwards and forces the eccentric cam end of the lever over the surface of the large roller 79. In this action, lever 69 straightens out to its horizontal position, whereby a strong compressive force is transmitted through the ram jaws and dies to effect a crimping action upon the wire terminal elements 38, as appears in Fig. 8.

The first member 108 of the roller elements of the roller cage is intended to provide a slight frictional drag on the cage so as to enable a rapid movement of the wedge over the needle bearings and a consequent rolling rather than a skidding movement of the cage over the shoulders 115. Due to the friction roller 108, the cage moves relatively slower than the wedge, so that the wedge is fully supported along its underside when it applies a final strong lifting force to lever 69. The friction roller 108 comprises (Fig. 4) a pair of pin elements slidably disposed in opposite ends of a cross bore of the center rail 106, and an intermediate spring which presses the pins outwardly so as to frictionally engage the ends of the pins with the side plates 25, 25'. An upstanding lug 121 formed at the rear of the center rail of the roller cage extends into a vertically deeper end portion of the under track 105 of the wedge. The resultant shoulder 122 formed in the underside of the wedge is adapted to engage this lug on a return movement of the wedge and thus carry the roller cage back to normal position. In the latter action, an upstanding lug 123 (Fig. 8) at the rear of a side shoulder 115 will prevent the roller cage from overriding its normal position.

The work piston 104 that drives the wedge is pneumatically powered, and is reciprocated in response to pneumatic fluid caused to flow by a trigger controlled arrangement of valves (Figs. 1, 2, 7, 7a, 8a, 9, 10).

Operating pressure air is supplied to the valve block 22 by a hose line, not shown, connected to the inlet 53

(Figs. 2, 7a). A pressure air distributor valve 124 is slidable in a chamber formed by a bushing 125 fitted in an open ended bore of the valve block. The opposed ends of the bore are sealed over in suitable manner by the elements 126 and 127. Valve 124 has a reduced central portion 128 which extends freely through a central neck passage 129 of the valve chamber. A conical shoulder 131 at one end of the reduced valve portion normally seats over an opposed O-ring so as to seal an annular supply inlet channel 132 from the neck passage 129 and from radial ports 133 that lead out of the neck passage to a passage 134 communicating with the work piston chamber 21. When the conical shoulder 131 is seated, an O-ring 135 mounted in a shoulder at the opposite end of the reduced portion 128 of the valve is unseated from the opposite end of the neck passage 129, whereby the latter passage is vented by a port 136 to atmosphere. When valve 124 is in its opposite position, as in Fig. 10, the O-ring 135 is seated so as to close the neck passage 129 off from the vent, and the conical shoulder 131 is unseated so as to communicate passage 129 with the supply inlet 53.

After turning a supply valve on, not shown, in the hose line connected to the inlet 53, the tool is conditioned, as in Figs. 7 and 7a, for operation. Pressure air thereupon flows through the inlet 53 into the branch passage 54 leading directly to the chamber 55 of the check valve 56, the function of which was earlier described. Branch passage 54 also connects directly by a lateral line 137 to the forward ends of the chambers 138 of a pair of return pistons 139 (Figs. 2 and 7). The latter have elongated stems 141 which pass through the main piston chamber and are anchored at their ends 142 in diametrically opposed portions of the work piston. The chambers 138 of the return pistons are formed forwardly of the work piston chamber in the wall of the housing of the tool. The total of the effective areas of the return pistons is relatively less than that of the work piston.

Pressure air admitted to the inlet 53 also flows (Fig. 7a) into the annular channel 132. From the latter it enters a radial port 143 to a central passage 144 in the valve, and then passes out at the lower end of the latter through a radial port to the lower end 146 of the valve chamber, just above the inner area of an enlarged end-head 147 of the valve; whereby the conical shoulder 131 of the valve is held seated over the neck passage 129, and the O-ring 135 is held unseated from the opposite end of this passage so that the latter is open to vent 136. The radial port 133 leading from passage 129 into the work piston chamber 21 is also vented in this normal condition of the distributor valve.

A branch passage 148 leading off the annular channel 132 connects with a chamber 149 of a throttle valve 151. The latter is normally seated over an O-ring so as to seal chamber 149 off from a passage 152. A reduced stem portion of the throttle valve extends freely through the latter passage to the outside of the valve block. A retainer 154 fixed on the right end of this valve stem carries an O-ring which is normally unseated from the adjacent open end of passage 152, whereby the latter is normally vented to atmosphere. Fitted to the tail end of the throttle valve is an arm 156 of a slide member 157 which is slidable in a counterbore 158 of the valve block. This counterbore is a continuation of a slightly narrower elongated bore 159. The latter extends through the bottom wall area of the housing and opens (Fig. 7) out into a radial recess 161 at the underside of the housing. An elongated draw rod 162 extends slidably through both bores 158, 159 and through the slide member 157. A threaded end portion of the draw rod projects in part to the outside of the slide body and carries an adjustable retaining nut 163 threaded into abutment with the slide member. A coil spring 164 compressed in the counterbore between a shoulder

of the latter and an opposed end of the slide member constantly urges the draw rod 162 rearwardly, whereby the throttle valve 151 is normally held seated. The pressure of this coil spring upon the throttle valve is adjustable by tightening or loosening the retaining nut 163.

A hooked free end 165 of the draw rod extends into the recess 161 of the housing and is attached to a hooked end of a trigger draw bar 166. The latter slides in a channel track 169 (Fig. 4) formed in the head portion of the trigger supporting section 112. An eye piece 167 terminating the forward end of the trigger bar projects into an end bifurcation 168 of the trigger supporting section. This eye piece is freely looped about a suitable cross pin in a bifurcation of a manually operable trigger 171. The latter pivots at 172 in the bifurcation 168.

It is clear that a counterclockwise movement of the trigger 171 (Fig. 8) will act to press the throttle valve forwardly, as in Fig. 10, whereby the O-ring on retainer 154 will be seated to close passage 152 off from vent, and the throttle valve 151 will be unseated to communicate the air supply chamber 149 to passage 152. Following this action, pressure air supplied over passage 148 to chamber 149 will enter passage 152 from where it will flow over a branch 173 in the valve block to the distributor valve chamber immediately below the underside 174 of an enlarged head end 175 of the distributor valve. The area of the underside 174 of this head end is relatively greater than the inner area 146 of the opposite head end 147, so that the greater pneumatic pressure acting on the area 174 shifts the distribution valve from its normal position to its opposite position as in Fig. 10. This shift unseats the conical shoulder 131 and seats the O-ring 135, whereby the neck passage 129 is open to the pneumatic supply line 53 at one end and is closed at its opposite end from vent 136.

Pressure air now enters through passages 129, 132, 133, 134 to the work piston chamber 21 to drive the piston and the associated wedge forwardly to effect a crimping action, as earlier described. In this forward movement of the work piston, the return pistons 139 are carried forwardly in their chambers 138. Any air trapped in the latter will be forced by this action to flow back over passage 54 to the inlet 53. When the work piston has completed its forward stroke (as in Figs. 8, 8a), air pressure builds up in chamber 21 at the rear of the work piston and also in a connected small ante-chamber 176 of the valve block. The latter chamber is normally sealed at one end by a pop-off valve 177 (Fig. 7a). The latter works in a relatively larger control valve chamber 178 of the valve block and is loaded by a compression spring 179 to normally seat an O-ring retainer 190 over the open end of the ante-chamber 176. The opposite end of the compression spring sleeves over a spring guide 181 and abuts a shoulder at the end of the latter. A set screw 182 threaded through a cap plug 183 engages the spring guide and serves to adjust the pressure of spring 179 against the pop-off valve so as to predetermine the build-up pressure required in the work piston chamber to unseat the pop-off valve. The compression spring 179 projects through opposite open ends of a control slide valve 184. The latter is slideable rearwardly of the pop-off valve in the control valve chamber 178.

The control valve has a peripheral channel 185 which normally registers with a passage 186 connected with the branch 173 leading from the throttle valve. An O-ring retainer 187 fixed upon the control valve carries an O-ring which normally seats upon a shoulder 180 formed by a rear enlargement 188 of the control valve chamber. A compression spring 189 disposed between this O-ring retainer and the inner wall of the cap plug 183 normally holds the O-ring seated on this shoulder, whereby pressure air in passage 186 is prevented from passing by way of channel 185 through the control valve 75

chamber to a passage 191 that leads to the top end 192 of the distribution valve chamber.

(Figs. 8, 8a.) As air pressure builds up in the work piston chamber, upon completion of the work stroke of the work piston 104, it reaches a degree at which the pop-off valve 177 unseats. The pressure air then flows into the control valve chamber ahead of the pop-off valve and acts upon the relatively large O-ring retainer 190 of the pop-off valve, which retainer previously was disposed behind the shoulder 193. The pop-off valve accordingly is forced back against the load of spring 179 into abutment with the control valve 184, and shifts the latter rearwardly. This unseats the O-ring retainer 187 from the shoulder 180, whereupon channel 185 is caused to communicate passage 186 through the enlargement 188 of the control valve chamber with passage 191. Pressure air thereupon flows to the top end 192 of the distribution valve chamber, and causes the distribution valve 124 to shift in the opposite direction back to normal position, whereupon the supply passage 53 is again closed to the work piston chamber 21 and the latter is again opened to vent 136. Since the pressure air in the chambers 138 of the return pistons 139 is at all times at line pressure, the latter are caused to restore and return the work piston following the return of the distribution valve to normal position.

As the work piston restores, the air trapped at its rear vents through passages 134, 129, 136. The pop-off valve 177 next restores, as in Fig. 9, under the load of its spring 30 as the air pressure in chamber 21 relaxes, but the control valve 184 is unable at this time to restore under the load of a spring 189 because the pressure of air in the enlarged portion 188 of the control valve chamber now acting against the relatively large O-ring retainer 187 is 35 relatively stronger than the opposing force of spring 189 at this time. However, after the trigger 171 is manually released, the throttle valve 151 is reseated by its spring 164 to normal, as in Fig. 7a, whereupon air trapped in passages 186, 173 flows around the stem of the throttle valve 151 to vent, whereupon the control valve restores. Air trapped in the head end 192 of the distribution valve chamber and in the connected passage 191 leaks around the outer diameter of the O-ring retainer 187 to the space at the rear thereof from where it escapes through vent holes 195 in the cap plug.

An interlock feature (Figs. 3 and 7) associates the trigger 171 with the operation of the check valve 56, so that the trigger may not be actuated while the push button 65 of the check valve is depressed and the check valve is allowing flow of pressure air to the holding piston 39. 50 This is a safety measure to prevent an accidental compressive movement of the wedge 99 while the jaws 33, 35 are temporarily held open by the depressed condition of the push button 65. To this end, the port 58 from the check valve passage 57 leads to the chamber 59 in which the slide member 61 works. The light compression spring 66 within the latter chamber holds this slide member in a position at the right so as to uncover the open end of a vertical bore 197 which runs down through the wall of the housing to the outside. An interlock rod 198 hooked at its bottom end in a cross hole 199 of the trigger, extends upwardly into this bore. When the trigger is in its released condition, the upper end of the interlock rod is just below chamber 59, as in Fig. 3. Now, when the trigger is actuated, the rod will obviously be moved up into chamber 59. If, however, the push button 65 has been depressed and is held depressed, pressure air will enter the chamber 59 and will force the interlock slide member 61 to cover over the open end of the bore 197. 60 While the latter condition exists, it is obvious that the trigger mechanism cannot be actuated since the interlock rod will be blocked by the slide member 61 from moving upward. When the push button is released, pressure air trapped in the passage 62 leaks around the

beveled nose of the slide member 61 and around the outer diameter of the push button to vent.

While an embodiment of the invention has been illustrated and described above, it is to be expressly understood that the invention is not limited thereto. Various changes can be made in the design and arrangement of the parts without departing from the spirit and scope of the invention as the same will now be understood by those skilled in the art, and it is our intent, therefore, to claim the invention not only as shown and described but also in all such forms and modifications thereof as may be reasonably construed to be within the spirit of the invention and the scope of the appended claims.

What is claimed is:

1. In a hand tool of the character described including a housing, a yoke member affixed to one end of the housing and having a stationary jaw, and a movable jaw member closable upon the stationary jaw; a piston chamber formed in the housing, a holding piston movable in the latter chamber, in parallel relation to the movable jaw, an arm connecting the piston with the movable jaw member for movement of the latter upon movement of the piston, a spring load normally loading the piston in a particular direction wherein the movable jaw member is held moved to a position closed upon the stationary jaw, and control means for controlling admission of pressure air to the piston chamber to drive the piston in the opposite direction against the spring load so as to move the movable jaw member to open position.

2. In a hand tool as in claim 1, wherein the control means comprises a pressure air supply line to the piston chamber, and a push button operable check valve in the supply line having a normally closed position.

3. In a hand tool as in claim 1, wherein the movable jaw member is characterized by a tail portion having a shoulder at the end thereof, and wherein a latch block is slidable in the housing at right angles to the jaw member and when the jaw member is moved to open position the latch block is adapted to engage with the tail portion in front of the shoulder so as to restrain the movable jaw member against movement to closed position, and wherein manually operable lever means is associated with the latch block for actuating the latter to and from engagement with the said shank portion.

4. In a hand tool as in claim 2, wherein the stationary jaw and movable jaw member have die elements adapted to receive therebetween work material subsequent to movement of the movable jaw member to open position, a power driven wedge is slidable in the housing, and means is provided in the housing for engagement by the driven wedge for transmitting a power movement of the wedge to the movable jaw member so as to compressively close the latter upon the work material.

5. In a hand tool as in claim 4, wherein the wedge is powered by a piston, valve means control a flow of pneumatic fluid to drive the piston, and a manually operable trigger is arranged for actuating the valve means.

6. In a hand tool as in claim 5, wherein interlock means is arranged to prevent operation of the trigger while the push button is in actuated condition, and comprises an interlock chamber in the housing, a member slidable in the latter chamber, a rod connected at one end to the trigger and normally slidable at the opposite end into a hole of the interlock chamber upon slight actuation of the trigger, spring means normally holding the slidable member clear of the hole, and passage means to the interlock chamber connectable with the pressure air supply line upon actuation of the push button, whereby the pressure air admitted to the interlock chamber is adapted to move the slidable member to a position over the hole to block entry of the rod into the latter.

7. In the combination of a housing, a ram member slidable in the housing in a longitudinal direction, a power driven wedge movable in the housing in a longitudinal direction, and means for translating a longitudi-

nal forward movement of the wedge into a corresponding movement of the ram member, wherein the translating means comprises a roller bearing member, a stationary support for the latter, a lever between the rear end of the ram member and the bearing member, means associating the lever at one end for pivot movement relative to the ram member, spring means normally supporting the lever to the ram member in a horizontal plane wherein the longitudinal axis of the lever is aligned with that of the ram member, and a cam surface defining the opposite end of the lever, the lever being adapted to move rearwardly with the ram member upon a rearward movement of the latter whereby the cam surface is caused to abut and ride downwardly over the bearing member and cause the lever to pivot downward as it does so, and the lever being adapted to pivot upwards to its horizontal position upon a forward movement of the wedge against the underside thereof whereby the cam end of the lever is caused to ride upwardly over the surface of the bearing member and the ram member is caused to move forwardly as the cam end of the lever so rides.

8. In the combination as in claim 7, wherein the means associating the lever with the ram member for pivot movement comprises a rounded nose at the forward end of the lever abutting the rear of the ram member, a spring plate mounted atop the lever and having a lip extension overlying the ram member, and an under lip extension of the lever underlying the ram member, the upper and lower lips serving to prevent the lever from slipping free of the ram member in a vertical plane.

9. In the combination as in claim 8, wherein an abutment of the housing overlies the lever, being in close proximity to the lever when the latter is in a horizontal plane, the lever being adapted to strike this abutment in the event of an abnormal overrise thereof above its horizontal plane, and the lip extension of the spring plate adapted to resiliently react against the surface of the ram member in the event of such overrise action of the lever.

10. In the combination as in claim 7, wherein the lever is characterized by depending roller means engageable by the wedge in the forward sliding movement of the latter.

11. In a crimping tool including an elongated housing having a piston chamber and a thickened wall area forwardly of the latter, the wall area having elongated bores therein parallel to the piston chamber, a work piston movable in the piston chamber, and a pair of elongated rods parallel to the longitudinal axis of the work piston and fixed at one end to diametrically opposite portions of the forward face of the latter piston; a pair of return pistons formed at the opposite ends of the rods and adapted to move in the said bores in the said wall area, a pressure air inlet to the housing, a first branch passage from the inlet leading directly to the said bores for continuously conducting pressure air from the inlet to drive the return pistons in a rearward direction relative to the housing, a second branch passage from the inlet for conducting pressure air to the piston chamber to drive the work piston forwardly, the return pistons having a total diameter relatively less than that of the work piston whereby pressure air from the inlet conducted simultaneously to both the return pistons and the work piston will drive the latter forwardly, pressure air flow control valve means associated with the second branch passage for controlling a flow of pressure air from the inlet to the piston chamber so as to cause the work piston to move in a forward direction, manually operable means for actuating the said valve means, and other valve means responsive to a predetermined pressure in the piston chamber at the end of the forward stroke of the work piston for automatically shutting off the flow of pressure air from the second branch passage to the piston chamber and communicating the piston chamber with vent.

12. In the combination comprising a housing, a ram member slidably therein, a wedge element slidably forwardly and rearwardly in the housing, means disposed between the wedge element and the ram member for translating a forward sliding movement of the wedge element into a forward sliding movement of the ram member, and means providing roller support to the wedge element in its sliding movement; wherein the latter means comprises a trackway formed in the housing below the path of movement of the wedge, a pair of shoulders bordering the trackway, and a ladder roller cage having a thick center guide rail movable in the trackway and having a series of roller pins projecting from opposite sides of the rail adapted to roll upon the shoulders, and the wedge element having a pair of depending longitudinal shoulders contacting the roller pins and adapted to ride upon the latter as the wedge moves.

13. In the combination as in claim 12, wherein the ladder roller cage has a normal position relative to the trackway and reacts to the sliding movement of the wedge to follow in the direction of the latter, wherein the ladder roller cage has an upstanding ear at its rear, and the wedge has an under shoulder engageable with this ear upon a rearward movement of the wedge, where by this engagement the ladder cage is adapted to be returned to its normal position.

14. In the combination as in claim 13, wherein the ladder roller cage is longer than the longitudinal shoulders of the wedge, a forward portion of these shoulders normally rests upon the roller pins and a rear portion overhangs the rear end of the ladder roller cage, and means is provided to cause the ladder roller cage to move relatively slower than the wedge in reaction to the movement of the latter whereby the longitudinal shoulders of the wedge are progressively caused to fully ride upon the roller pins of the ladder cage.

15. In a pneumatically powered tool including a work piston, a plurality of return pistons attached to the work piston for movement together with the work piston and having a total effective area relatively less than that of the work piston, a housing providing chambers for the work piston and the return pistons and having a valve block and a pressure air inlet to the valve block common to the chambers of the work piston and of the return pistons; valve means actuatable for admitting pressure air from the inlet to the chamber of the work piston to drive the work piston on a power stroke and normally blocking such admission of pressure air, manually operated means for actuating the valve means to admit such pressure air to the work piston chamber, and other means responsive to a predetermined value of pressure air in the work piston chamber after completion of the power stroke of the work piston to render the valve means ineffective to supply further pressure air to the work piston, whereby pressure air from the common inlet to the return pistons is effective to operate the latter to return the work piston.

16. In a pneumatically powered tool including a work piston, and a pair of return pistons attached to the work piston for movement together with the latter and having a total effective area relatively less than that of the work piston; a common source of pressure air connected to both the work piston and the return pistons, control means effective in one condition for admitting pressure air from the common source simultaneously to the work piston and to the return pistons whereby the work piston is caused to move on a power stroke, and effective in a second condition for blocking flow of pressure air to the work piston and allowing flow of

pressure air to the return pistons whereby the return pistons are driven to return the work piston, manually operable means for placing the control means in its first condition, and means responsive to a predetermined degree of pressure arising at the rear of the work piston after completion of the work stroke of the work piston to place the control means in its second condition.

17. In a pneumatically powered tool including a work piston effective upon a power stroke to actuate one element relative to another, a pair of return pistons attached to the work piston for movement together with the latter and having an effective area relatively less than that of the work piston, a housing providing separate piston chambers for the work piston and the return pistons, a valve block at one end of the housing, a pressure air inlet to the block being common to the chambers of the work piston and of the return pistons, control means normally stopping flow of pressure air from the inlet to the chamber of the work piston and not to the chambers of the return pistons, manually operable means associated with the control means to actuate the latter to discontinue the stoppage of flow of pressure air to the chamber of the work piston whereby the differential in pressures of air acting on both the return pistons and the work piston causes the work piston to execute a power stroke carrying the return pistons with it, and other means automatically responsive to a predetermined development of pressure in the work piston chamber after completion of the said power stroke to actuate the control means to again stop flow of pressure air to the chamber of the work piston and not to the return pistons whereby the return pistons are caused to move in the opposite direction and to carry the work piston with them.

18. In the combination of a tool of the character described including a pneumatically powered work piston movable in a piston chamber, and a source of pressure air; a system of interacting slide valves interposed between the source and the piston chamber, comprising means normally applying pressure air from the source to the valve system whereby the latter is maintained in a normal condition blocking flow of pressure air from the source to the piston chamber, manually operable means connected to the valve system effective in an operated condition to vary the directional application of pressure air from the source to the valve system whereby the latter is caused to be shifted to a second condition allowing flow of pressure air from the source to the piston chamber to drive the piston over a power stroke, means responsive to a predetermined build-up of air pressure in the piston chamber subsequent to the power stroke of the piston to vary the directional application of pressure air from the source to the valve system so as to shift the latter to a third condition wherein the valve system discontinues flow of pressure air from the source to the piston chamber, and other means effective upon manual release of the manually operated means to cause a directional variation of the application of pressure air from the source to the valve system to restore the latter to its normal condition.
